UNITED STATES PATENT OFFICE.

ALFRED C. GILBERT, OF NEW HAVEN, CONNECTICUT, ASSIGNOR TO THE A. C. GILBERT COMPANY, OF NEW HAVEN, CONNECTICUT, A CORPORATION OF CONNECTICUT.

DESIGN FOR A TOY BUILDING ELEMENT.

51,277.

Specification for Design.

Patented Sept. 18, 1917.

Application filed November 19, 1914. Serial No. 873,058. Term of patent 14 years.

To all whom it may concern:

Be it known that I, ALFRED C. GILBERT, a citizen of the United States, residing in the city and county of New Haven and State of Connecticut, have invented a new, original, and ornamental Design for a Toy Building Element, of which the following is a specification, when taken in connection with the accompanying drawing.

In the drawing,

Figure 1 is a front face view of a toy building element embodying my design;

Fig. 2 is a rear face view of said element;

Fig. 3 is a side edge view of said element; and

Fig. 4 is an end view of the same.

The design is characterized by the thinness of the metallic strip, the provision of a strip of this character with a body part having extended ends and intermediate cut-

out parts forming regularly spaced angularly disposed lattice parts and the forwardly offset side bars, each of said side bars having forward struck up projections, the projections on one side being arranged alternately with those on the other side, and said projections being arranged adjacent the point of connection of the side bars with the angularly disposed lattice strips. A further feature of the design includes the rearwardly projecting angularly disposed flanges on the side bars.

What I claim is:—

The ornamental design for a toy building element, substantially as shown.

ALFRED C. GILBERT.
